(57) **CLAIM**

The ornamental design for a display box, as shown and described.

DESCRIPTION

In a preferred embodiment, the nature of this product is as a display box for a product sold at retail, such as a lamp.

FIG. 1 is a front perspective view from above and to one side of a display box embodying our new design;

FIG. 2 is a right side elevational view thereof;

FIG. 3 is a top plan view thereof;

FIG. 4 is a front view thereof;

FIG. 5 is a rear view thereof;

FIG. 6 is a left side elevational view thereof;

FIG. 7 is a bottom plan view thereof;

FIG. 8 is a front perspective view from above and to one side of a second embodiment of a display box identical to the first embodiment in rear view, left side view and bottom view, and identical to the first embodiment except that the header flaps at the top portion of the front and right side of the box have been pulled outward;

FIG. 9 is a right side elevational view thereof;

FIG. 10 is a top plan view thereof; and,

FIG. 11 is a front view thereof.

The broken line representations of sealing flaps on the rear panels of the embodiments of FIGS. 1-3 and 5-10 are shown for the purposes of illustration only and form no part of the claimed design.
